UNITED STATES PATENT OFFICE.

EUGÈNE MARIE VILLEROY, OF SCHRAMBERG, WÜRTEMBERG, GERMANY.

CRUSHING-MILL.

SPECIFICATION forming part of Letters Patent No. 318,670, dated May 26, 1885.

Application filed January 28, 1885. (No model.)

To all whom it may concern:

Be it known that I, EUGÈNE MARIE VILLEROY, a citizen of the French Republic, and a resident of Schramberg, in the Kingdom of Würtemberg, and German Empire, have invented certain new and useful Improvements 5 in Crushing-Mills, of which the following is a specification.

My invention relates to improvements in mills for crushing clay, stones, and similar material; and the objects of my improvements are the application of a rolling ball for crushing the said material inside of or within the recess of a rotating and oscillating or swinging 10 basin and the means for adjusting the inclination of this basin. I attain these objects by the mechanism illustrated in the accompanying 15 drawings, in which—

Figure 1 is a side elevation, partly in section, of a crushing-mill with inclined rotating basin. Fig. 2 is a front view thereof; and Fig. 3, a top view of head-plate, showing the adjustable bearing of the inclined shaft.

Similar letters refer to similar parts throughout the several views.

According to my invention a heavy ball, *a*, of stone, iron, or other suitable material, is placed inside of or within the recess of a basin, *b*, in the center of which is fastened an upright shaft, *c*. This shaft *c*, which rests with its upper end in a bearing, *l*, and with the lower end in a bearing, *k*, is inclined toward the vertical.

In the construction, as shown by Figs. 1 to 35 3, the head-plate *g* is arranged movably in such a manner as to be raised or lowered on the col-

umns or stands *h*, in order to adjust conveniently the inclination of the shaft *c* and the basin *b* fixed thereon. The set screws *i* secure the plate *g* in the position required. The upper bearing, *l*, is therefore provided with pivots which rest in the adjustable support *m*. To the bottom of the basin *b* is fastened a geared ring, *d*, into which engages a rotating bevel-gear, *e*, thus causing the basin *b* to rotate. The 40 conical roller *f* supports the basin at its lowest point.

Having thus fully described my invention, what I desire to claim and secure by Letters Patent is—

1. In a crushing-mill, the combination of the inclined shaft *c*, the rotating basin *b*, the ball *a*, the adjustable bearing *l*, having pivots on the sides of it, and the adjustable support *m*, in which the said bearing is pivoted, substantially as and for the purpose set forth. 50

2. In a crushing-mill, the combination of the inclined shaft *c*, the rotating basin *b*, the ball *a*, the adjustable bearing *l*, having pivots on the sides of it, the adjustable support *m*, 55 in which the said bearing is pivoted, the vertically-adjustable plate *g*, and the stands *h*, substantially as and for the purpose set forth.

In testimony that I claim the foregoing as my invention I have signed my name, in presence of two witnesses, this 26th day of December, 1884.

EUGÈNE MARIE VILLEROY.
